UNITED STATES PATENT OFFICE.

NATHAN HARPER, OF NEWARK, NEW JERSEY.

DRIER-CAR FOR BRICKS.

SPECIFICATION forming part of Letters Patent No. 486,931, dated November 29, 1892.

Application filed July 21, 1892. Serial No. 440,775. (No model.)

To all whom it may concern:

Be it known that I, NATHAN HARPER, a citizen of the United States, residing in Newark, county of Essex, and State of New Jersey, have 5 invented certain new and useful Improvements in Drier-Cars for Bricks; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

The object of this invention is to provide 15 a drier-car for bricks or other clay products, whereby a large saving can be effected in the amount of fuel heretofore required in the drying process, while by the same means the capacity of the car and also of the drying-chamber are both largely increased without 20 any addition to the size of either.

The invention consists in the improved 25 drier-car and the combination and arrangements of the various parts thereof, substantially as will be hereinafter more fully described, and finally embodied in the clauses of the claim.

Similar letters of reference indicate corresponding parts in each of the several figures. 30 Figure 1 is a side elevation of my improved drier-car, together with its load of pallets carrying the bricks. Fig. 2 is a similar view of an ordinary drier-car, drawn to the same size as Fig. 1, and illustrates the difference in 35 the respective capacity of the two structures and in the disposition of the load on each. Fig. 3 is an end elevation of Fig. 1, placed in a drying-tunnel, and illustrates how completely the load on the improved car occupies all the space available within the tunnel. Fig. 4 is a top plan view of the improved car, and Fig. 5 is an enlarged sectional view on line x , Fig. 4.

In said drawings, a a represent the side bars or frame of the improved car, which are secured and held firmly in their respective positions by rods or braces c or in any other desired manner. Projections d extend upwardly from said side bars to receive or sustain boxes or bearings e and axles f carrying wheels g , all of which are secured in their respective places by any of the usual means.

These upwardly-extending projections may be constructed and arranged in any desired manner and of such height and width as is 55 preferred. In the drawings they have the height of two courses of pallets and the width of one. The pallets h , containing the bricks to be dried, are placed on the top of the frame a and its respective projections d , as indicated in Figs. 1 and 3. In these figures it will be seen that the tops of the side bars a are carried down as closely as possible to the rails i , thereby permitting substantially all the space from the surface of the 60 rails to the top of the drying-tunnel B to be occupied with bricks. The top of said side bars or frame may of course be constructed at any height desired below the top of the wheels. Should the top of said frame be carried high 70 enough to receive the axles of the wheels, the upwardly-extending projections would in such case have nothing to sustain but the brick pallets placed thereon.

In all drier-cars heretofore used the top of 75 the frame or side bars has always been arranged as high or higher than the top of the wheels, as illustrated at a' , Fig. 2, whereby all the space between the top of said frame and the surface of the rails i has been unoccupied 80 with bricks, therefore unutilized. As thus constructed the area of the unoccupied space beneath the car is nearly equal in extent to the combined area of all the spaces between the bricks, and as this latter area is divided 85 by the bricks into a large number of narrow channels which greatly impede the passage of the air-currents, while all the space beneath the car is united in one large open channel, the result is that fully one-half of all the 90 heated air drawn through the drying-chamber passes beneath the car without coming in contact with the bricks thereon and is thus wasted, thereby causing the loss of about one-half the fuel used. On my improved car the 95 bricks can be loaded close down to the surface of the rails, thus compelling substantially all the air traveling through the drying-chamber to pass directly between the various courses of bricks, thereby utilizing the heat 100 to the fullest possible extent and reducing the consumption of fuel in a corresponding degree.

By comparing the load on the improved car,

Fig 1, with that on the ordinary car, Fig. 2, it will be seen that the invention enables the improved car to receive over twenty percent. more bricks than the ordinary car without requiring any more space. This increased capacity of the improved car will admit the drying of a correspondingly-larger product of bricks without any addition to the number or size of the cars or to the area of the drying-chamber, while the quantity of fuel necessary for drying this larger product will be very much less than would be required for the smaller product with the ordinary car.

I do not intend to limit myself to the construction herein shown and described, as various modifications may be made without changing the scope of my invention, the main object of which is to provide a drier-car on which the bricks can be placed at a lower level than the top of the wheels, thereby economizing both car-space and fuel.

Having thus described my invention, what I claim as new, and desire to secure by Letters Patent, is—

25 1. In a brick-drier car, a longitudinal supporting-frame constructed and placed on the outer side of the wheels of said car and adapted to receive and sustain brick-carrying pallets below the level of the top of and beyond said wheels, substantially as and for the purposes set forth.

2. In a brick-drier car, a longitudinal supporting-frame constructed and placed on the outer side of the wheels of said car and adapted to receive and sustain brick-carrying pallets below the level of the axles and extending beyond said wheels, substantially as and for the purposes set forth.

3. In a brick-drier car, the combination, 40 with the wheels, of a longitudinal supporting-frame constructed and placed on the outer

side of said wheels and having its top arranged at a lower level than the top of said wheels, said frame being adapted to receive and sustain brick-carrying pallets below the level of the top of said wheels, substantially as and for the purposes set forth. 45

4. In a brick-drier car, the combination, with the wheels, of a longitudinal supporting-frame constructed and placed on the outer side of said wheels and having its top arranged at a lower level than the axles of said wheels, said frame being adapted to receive and sustain brick-carrying pallets below the level of the axles of said wheels, substantially as and 55 for the purposes set forth.

5. In a brick-drier car, the combination, with the wheels, of a frame with its top arranged at a lower level than the top of said wheels, and projections extending upwardly 60 from said frame to or above the top of said wheels, said projections and said frame being adapted to receive and sustain brick-carrying pallets on their different respective levels, substantially as described. 55

6. In a brick-drier car, the combination, with the wheels, of a frame with its top arranged at a lower level than the axles of said wheels, and projections extending upwardly 70 from said frame to receive or sustain the said axles carrying said wheels, said projections and said frame being adapted to receive and sustain brick-carrying pallets on their different respective levels, substantially as described. 75

In testimony that I claim the foregoing I have hereunto set my hand this 11th day of July, 1892.

NATHAN HARPER.
